United States Patent Office

Des. 178,857
Patented Oct. 2, 1956

178,857

GLOVE HOLDER CLASP

Henry N. Armbrust, Jamestown, R. I.

Application September 28, 1955, Serial No. 38,140

Term of patent 3½ years

(Cl. D17—3)

Fig. 1.

Fig. 2.

Fig. 3.

Fig. 1 is a side elevational view of a glove holder clasp showing my new design;

Fig. 2 is a top plan view of the clasp; and

Fig. 3 is a bottom plan view thereof.

I claim:

The ornamental design for a glove holder clasp, substantially as shown.
